LESLIE R. NORMAN AND WILLIAM F. DIETERICHS, JR., OF ST. LOUIS, MISSOURI

Letters Patent No. 61,448, dated January 22, 1867.

IMPROVED BRICK-KILN.

The Schedule referred to in these Letters Patent and making part of the same.

TO ALL WHOM IT MAY CONCERN:

Be it known that we, LESLIE R. NORMAN and WILLIAM F. DIETERICHS, Jr., both of the city and county of St. Louis and State of Missouri, have invented a new and useful improvement in "Kilns" for Burning Bricks, Tiles, Earthenware, &c., &c.; and we do hereby declare that the following is a full and clear description thereof, reference being had to the accompanying drawings, and to the letters of reference marked thereon.

This invention relates, firstly, to the construction of the walls of the kiln, which are arched over the top of the chamber wherein the articles are to be burned, and the said arch is to be formed of two thicknesses of wall, so as to leave a chamber between for purposes of ventilation or escape of the steam that will generate within the kiln during the early part of the process of burning; and this construction of the walls of the kiln also has the effect to retain and economize the heat; secondly, this invention relates to the arrangement of the draught or smoke flues, and also to the cold-air flues that supply the cold air to the kiln; thirdly, the invention relates to the ventilating devices for conducting the steam from the interior of the kiln into the air and steam chamber between the two arches, and from thence into the open air outside of the kiln; fourthly, the invention relates to the construction of the walls of vertical sides of the kiln in a concave form, so as to resist the expanding force of the heat within, and also the expanding force of the steam that will be generated from the bricks or other articles that are being burned, and which expanding force would tend to burst the kiln asunder.

To enable those skilled in the art to make and use our improved kiln, we will proceed to describe its construction and operation.

Figure 1 of the drawings is an elevation in perspective of one of the improved kilns.

Figure 2 is a longitudinal vertical section.

Figure 3 is a transverse vertical section.

Figure 4 is a horizontal section, showing the plan of the floor and furnaces within the kiln.

The kiln is to be entirely enclosed by brick-work or masonry, and the whole of the interior of it should be formed of fire-brick. The top of it should have a double arch, A A¹ thrown over it, so as to leave an open chamber, A², between the upper and lower arch. The lower arch, A, has numerous perforations, *a*, through it, so as to permit the steam and hot gases that may be generated within the kiln to pass up into the said chamber A², from whence they may escape through the apertures in the outer walls of the kiln, that are closed by the small ventilating doors *a'*. During the early part of the process of burning, the doors *a'* will be open so as to permit the steam to escape without injuring the walls of the kiln, otherwise the expansive force of the steam would endanger the cracking or bursting of the walls, and thereby injure or destroy the kiln. After the fire shall have been burning a sufficient length of time to drive off all the steam that may be generated from the moisture of the articles that are being burned, the doors *a'* are to be closed so as to confine the heated air in the chamber A², and this hot-air chamber interposed between the inner and outer walls of the kiln will greatly economize fuel by the prevention of the loss of heat by radiation. The furnaces B are arranged in the usual manner of the furnaces of brick-kilns, *i. e.*, running entirely across the bottom of the kiln, and having doors, *b*, through which the fuel is fed into them. The doors *b'* are intended to open into the ash-pits, for the purpose of removing refuse matter therefrom. The air that is to feed the furnaces is to be conducted in pipes (not shown) underground into the air-boxes C, whence it is permitted to pass through the orifices *c* into the furnaces. These orifices *c* are to be distributed along the entire length of the furnaces, so as to afford an equal distribution of air to all parts of the furnace. This construction is clearly shown in fig. 3. There are smoke-flues, D, built of fire-brick, on the tops and outer ends of the air-chambers C, as clearly shown in figs. 3 and 4. These flues are connected by means of the short transverse flues *d* with the discharge flues D¹, which terminate in the chimneys D² above the top of the kiln. The construction of the flues D¹ is clearly shown in fig. 3. By this construction a large part of the heat that would otherwise escape with the smoke is absorbed by the brick-work surrounding the said flues, and so retained in the kiln, and thus economized. The plan of the vertical walls of the kiln should be concave on the outer sides, as shown clearly in fig. 4. They should also be strengthened by means of horizontal iron bands, (not shown,) and similar iron bands or braces should also be used in the walls

vertically. This concave construction of the walls will greatly strengthen them and prevent the bursting of them by the expansive force of the confined heat or steam within the kiln.

Having described our invention, what we claim, is—

1. The construction and arrangement of the smoke-flues D and D', as described and set forth.
2. We claim the cold air or supply-chambers C, and the distribution of the air to the furnaces through a series of orifices, c, as described and set forth.
3. We claim the construction of the vertical walls of the kiln with concave sides, so as to resist the interior pressure from the expansive force of the heat and steam.

LESLIE R. NORMAN,
WILLIAM F. DIETERICHS, JR.
